UNITED STATES PATENT OFFICE.

ALFRED JOHN HAYDEN, OF DAYTONA BEACH, FLORIDA.

AUTOMOBILE LUGGAGE CARRIER.

Application filed April 21, 1923. Serial No. 633,733.

To all whom it may concern:

Be it known that I, ALFRED J. HAYDEN, a citizen of the United States, and resident of Daytona Beach, in the county of Volusia and State of Florida, have invented certain new and useful Improvements in Automobile Luggage Carriers, of which the following is a specification.

My present invention relates to luggage carriers for automobiles or the like, and particularly that type of carrier adapted to be secured to or placed on, the running board of such a vehicle for the purpose of holding bags or luggage between itself and the body 15 of the vehicle.

The primary object of my invention is to provide such a device which will be efficient in operation, cheap to manufacture, easily installed, and which may be folded out of 20 the way when not in use which will obviate the necessity of removal from the vehicle.

To this end my invention consists in supplying certain instrumentalities whereby a retaining wall is hingedly connected to the 25 usual running board hangers so that the retaining wall may occupy either a horizontal position on top of the running board, or may be sprung outwardly to occupy a vertical position at the edge of the running 30 board. In this position the spring will prevent accidental displacement and the luggage may be placed in the pocket thus formed between the retaining wall and the body of the vehicle. A catch is utilized to prevent 35 the retaining wall from moving to a vertical position under action of its spring when it is desired to have the device folded downwardly against the running board.

I have illustrated a certain form of device in the drawings, but it is understood 40 that this is merely the present preferred form and that various changes may be made in the device shown and described without departing from the spirit of my invention.

45 In these drawings:—

Figure 1 is a perspective view showing the up-standing wall in the folded-down position.

Fig. 2 is a perspective view showing the 50 up-standing wall in vertical position.

Fig. 3 is a plan view of Fig. 2.

Fig. 4 is a detail of the running board support and actuating spring.

Fig. 5 is a sectional elevation of the 55 running board assembly.

Referring now to the drawings, I have

shown the automobile running board at 1 supported upon the usual hangers 2 extending outwardly from the frame of the automobile. In order to adapt these hangers to 5 receive the device of this invention, it is necessary to slot the top thereof in proximity to the end, as at 3, and to cut away that part of the top directly adjacent the end of the hanger. Thus the hanger in its 10 modified form, has side walls 4 extending outwardly to a point beyond the top 5, this latter portion having a longitudinal slot 3 therein. The upstanding wall is shown at 15 6 and may be made of any desired material such as wood, metal, rubber, or the like, and has secured thereto a hinge element 7 of substantially cross shape in which the short end 8 and the two side flaps 9 are deformed toward each other to form a four-sided box-like portion 10, for a purpose more fully hereinafter described. The hinge member 7 is secured to the part 6 in any 20 desired manner. A bolt 11 penetrates the parts 9 and is surrounded by a spring member 12 comprising a loop 12, and a coil 13 which is an extension of the loop 12 and in direct contact with the bolt 11, the two ends 14 of said spring projecting inside the hanger 2 and penetrating apertures in the walls 4 25 in order to securely position the same and prevent undue movement. The spring is coiled about the bolt 11 in such a manner that the loop 12 will exert pressure against the hinge member 7. The hinge member is placed in proximity to the end of the hanger 30 so that the flaps 9 project inside the walls 4 of the hanger, the cut away portions 10 fitting under that part of the top of the hanger on each side of the slot 3. Thus the hinge portion is secured to the hanger by two elements, namely the bolt 11 and the ends 14 of the spring. When the retaining wall 6 is folded downwardly on top of the running board, the loop 12 of the spring 35 passes through the slot 3 which allows the wall 6 to lie close to the running board.

A right angular element consisting of an elongated part 15 and an upstanding part 16 may be secured to the running board in any desired manner so that the part 16 projects upwardly at that part of the running board adjacent the body of the vehicle. Ears 17 are provided on the part 16 having perforations therein adapted to receive a bolt or pin 18 about which is coiled a spring 19 having ends 20 and 21 adapted to bear against 40 45 50 55 60 65 70 75 80 85 90 95 100 105 110

the upstanding part 16 of the right angular element and a catch member 22 respectively. This catch member is secured to the ears 17 also by the pin 18. Pressure of the spring 19 tends to force the bottom of the catch outwardly. Thus the offset portion 23 of the catch engages the edge of the retaining wall when it occupies a horizontal position and prevents movement thereof. When it is desired to place the retaining wall in vertical position, outward pressure upon the upper end of the catch 22 allows the spring 13 to act and the upstanding wall automatically takes its desired position.

15 Obviously vehicles having hangers constructed of other than inverted U material will require modified instrumentalities to accomplish the desired results. Likewise the hinge portion may be made of various pieces 20 placed together in divers manners, but it is to be understood that the maximum effi-

cency is to be obtained through the use of the preferred form of the device as illustrated.

Obviously the running board must be 25 slotted to correspond with the similar part 3 formed in the end of the hanger 2.

Having thus described my invention, what I claim is:—

A combination, a vehicle having a running board supported upon hangers, a retaining wall hinged to said hangers, spring means to hold the retaining wall in vertical position at the edge of the running board, the upper portion of said hanger being cut 35 away to allow the spring means to exert pressure upon the hinge portion when the retaining wall occupies both vertical and horizontal positions.

In testimony whereof, I affix my signature.

ALFRED JOHN HAYDEN.
